BRAKE HANGER BRACKET

David M. Light, Chicago, Ill., assignor to American Steel Foundries, Chicago, Ill., a corporation of New Jersey

Application December 4, 1937, Serial No. 178,059

16 Claims. (Cl. 188—209)

My invention relates to railway rolling stock and more particularly to a novel design of brake hanger bracket. As is well known, such brake hanger brackets are usually cast integrally with the side frame of the truck structure inasmuch as this member is in close proximity to the wheel and serves as a convenient means of support.

Present approved designs of open jaw brake hanger brackets have the jaws of the bracket cast at an angle between ten and fifteen degrees from the horizontal. As a rule the top and bottom walls are cast parallel and the slope of these walls leading into the pocket wherein the brake hanger is suspended is diagonally arranged as above indicated.

Under standard conditions with the brakes applied with new shoes and full diameter wheels, the brake hanger bracket is supported at an angle of between ten and fifteen degrees from the vertical. In other words, under the said standard conditions with new parts and the brakes in operative or applied position, the brake hanger is substantially normal to the lower wall of the jaw within which it is supported.

Since this is the case, it will be readily apparent to those skilled in the art that as wheel wear occurs and as the brake shoe itself is worn down, the brake hanger swings farther and farther from the perpendicular as such wear takes place. Under these conditions, an application of the brake power causes a certain resultant of forces tending to pull the brake hanger out of the jaw in which it is supported when the wheels are turning in a direction to pull downwardly on the hanger.

On the other hand, when the wheels are turning in the reverse direction so that there is an upward thrust on the hanger, the resultant of force is to direct the hanger into the pocket inasmuch as the hanger under such conditions of worn parts is disposed at an acute angle with respect to the plane of the top wall of the bracket against which it abuts on such upward thrusts. This latter movement of the hanger toward the closed end of the jaw under conditions of upward thrust is of course desirable and it would likewise be desirable to have the resultant of force when the thrust is downward operate likewise to urge the hanger toward the closed end of the jaw.

Under such conditions as those above described wherein the hanger is under certain conditions urged inwardly of the jaw and under other conditions urged outwardly thereof, it is extremely difficult to retain said wear plate in the brake

hanger jaw. This is due to the fact that the back-and-forth movement of the hanger itself as above described is transmitted to the wear plate and ultimately the wear plate is loosened or wears against its securing means.

It is an object of my invention to design a form of brake hanger bracket which will overcome the difficulties above described.

It is a further object of my invention to design a brake hanger bracket of such form that under conditions of normal operation neither the upward thrust nor the downward thrust of the hanger will have a resultant of force tending to urge the hanger out of the jaw.

A further object of my invention is to design such a brake hanger bracket as above described and a wear plate therefor which will be relatively free of vibration and thereby reduce wear between the wear plate and the brake hanger jaw.

Other novel features in my invention are set forth in the following specification and the appended claims together with the associated drawing.

Figure 1 is a side elevation of a side frame incorporating my invention, the view being taken from the inner face of said side frame;

Figure 2 is a top plan view of the frame and bracket structure shown in Figure 1, the view being taken substantially from the plane indicated by the line 2—2 of Figure 1;

Figure 3 is a sectional view through the brake hanger jaw, the section being taken substantially in the plane indicated by the line 3—3 of Figure 2;

Figure 4 is a top plan view of my novel form of wear plate;

Figure 5 is a transverse sectional view through the wear plate substantially in the plane indicated by the line 5—5 of Figure 4; and

Figure 6 is another transverse section through the wear plate, the section being taken substantially in the plane indicated by the line 6—6 of Figure 4.

Describing my novel form of brake hanger bracket in more detail as shown in the modification illustrated in the drawing, the cast steel side frame generally indicated at 2 has the compression member 4 and the integrally formed column 6. On the inner face of the side frame 2 and adjacent the juncture of the compression member 4 and the column 6 is the integrally formed brake hanger bracket generally designated 8, the juncture of said bracket with said compression member being reinforced by the ver-

tical web 9. The outer portion of said bracket 8 is a jaw-like structure having the top wall 10 and the bottom wall 12 forming therebetween the throat 14 within which may be seated the top 5 chord or transverse member 16 of the loop brake hanger 18 of usual form. Seated upon the bottom wall 12 is my novel form of wear plate generally indicated at 20, said wear plate, shown in more detail in Figures 4 to 6, being secured in 10 position by the retaining bolt 22, the head 24 of said bolt being received within the opening 26 and secured against rotation by engagement with the walls of said opening. The shank of the bolt 22 projects through the opening 28 in 15 the lower wall 12 and is secured in position by the lock nuts 30, 30. From a consideration of Figures 1 and 3, it will be apparent that the head 24 of the bolt 22 passes freely through the opening 26 in the top wall of the brake hanger 20 jaw and is seated against the central stud 32 of the wear plate as clearly shown at 34, 34, the shank of said bolt extending through the opening 36 centrally formed in said stud portion 32. At the rear of my novel form of wear plate 25 is formed the transverse channel 38 within which may be seated the cross bar or transverse member 16 of the brake hanger 18, the bottom surface of said transverse member 16 being cylindrical in form as best seen in Figures 1 and 3, 30 said cylindrical portion being formed on an arc of shorter radius than the channel portion 38 of the wear plate.

The bottom wall 12 of my novel form of brake hanger jaw is disposed at an angle from the 35 horizontal indicated at X (Figure 1), said angle being greater than twenty degrees and less than thirty degrees from the horizontal for a purpose to be more fully explained hereafter. The outer portion of the top wall 10 of said jaw is disposed 40 at a similar angle, but the throat portion of said upper wall is of novel form and that portion immediately above the transverse member 16 is of arcuate form to provide abutment for said transverse member 16 as at 40 (Figure 3). It will 45 be observed that the abutment at 40 of the cross bar 16 of the hanger is disposed at such an angle that there can be no resultant of force tending to move the hanger out of the jaw when upward thrusts of the hanger occur as in normal operation. In other words the extreme forward end 50 portion of the upper surface of said throat lies in a plane tangent to said end portion and forming an acute angle with the axis A—B and said plane as indicated at M—N (Figure 1) extends 55 through the open end of said jaw between the top and bottom walls thereof. The said forward portion may lie in any plane forming an acute angle with the plane of said hanger with the brakes applied.

60 As shown in Figures 1 and 3, the hanger 18 is disposed at the angle which it normally would assume if the brakes were applied with new brake shoes and new wheels as represented by the axis A—B. Under conditions of maximum wear, both 65 of the brake shoes and of the wheel and with the brakes applied, the hanger would assume the position indicated by the axis A—C. With the brakes released, the hanger under either of these conditions might assume the position indicated 70 by the vertical axis A—D. It will be apparent to those skilled in the art that upward thrust of the brake hanger can occur only when the hanger is in a position between the axes A—B and A—C because these represent the extremes of the possible hanger positions when the brakes are ap- 75

plied, and upward thrust can only occur with the brakes applied and the wheel rotating in a given direction. With the wheel rotating in the opposite direction of course there is a downward pull on the hanger. It is necessary, therefore, that 5 the configuration of the throat of the upper jaw where abutment of the hanger occurs as at 40 be such that no resultant of force outwardly of the jaw can occur when upward thrust is received from the hanger in any position between the axes 10 A—B and A—C. Inasmuch as the axis A—C is normal to the plane of the lower wall 12, the angling of this axis from the perpendicular is substantially twenty-five degrees as the angle of said wall 12 is similarly substantially twenty- 15 degrees from the horizontal as indicated by the arc X. Stated in another way, the normal position of the hanger with new shoes and wheels is indicated by the axis A—B, approximately fourteen degrees from the vertical as indicated by the axis A—D, the maximum range of the hanger's positions with the brakes applied is represented by the arc measured between the axes A—B and A—C, an arc of approximately eleven degrees. It is, therefore, necessary for the lower wall 12 20 of the brake hanger to assume an angularity from the horizontal at least equal to the sum of fourteen degrees plus eleven degrees or twenty-five degrees in order to prevent a resultant of force tending to move the hanger out of the jaw 25 under any possible operative conditions. At the same time the configuration of the upper throat of the jaw must be such as to prevent any resultant of force tending to move the hanger out 30 of the jaw when the thrust is upward as previously described. I have accomplished this by 35 making the upper throat of the jaw of arcuate form and having the forward portion of said upper surface lying in the downwardly directed plane N—M as previously described.

In addition to the side elevation of Figure 1 and the sectional view of Figure 3, my novel form of wear plate 20 is further shown in Figures 4 to 6, said wear plate comprising the bottom wall 40 45 45 - abutment of the top member of said hanger, the forward portion of said surface lying in a plane extending through the open end of said jaw below said top wall, and a wear plate secured on said bottom wall, said wear plate having an up-turned flange at its inner end defining one edge of a channel portion underlying said member and having at its outer end a down-turned flange for abutment against the outer extremity of said bottom wall, said bottom wall lying in a plane diverging from the horizontal through an arc at least equal to the arc which said hanger may diverge from the perpendicular under operative conditions.
15. 2. In a railway car truck, a frame member having a bracket with a brake hanger jaw defined by top and bottom walls merging in a throat, a loop hanger seated in said throat, the top surface of said throat having an area for abutment of the top member of said hanger, the forward portion of said area lying in a plane extending through the open end of said jaw below said top wall, and a wear plate secured on said bottom wall, said wear plate having an up-turned flange at its inner end defining one edge of a channel portion underlying said member and having at its outer end a down-turned flange for abutment against the outer extremity of said bottom wall.
3. A brake hanger bracket having an angularly disposed jaw defined by top and bottom walls merging in a throat, a wear plate secured on said bottom wall, and a loop type hanger seated on said plate in said throat, said bottom wall being disposed at an angle diverging from the horizontal an amount at least equal to the maximum angle said hanger may diverge from the perpendicular under operating conditions, the upper surface of said throat having an area for abutment of the top member of said hanger on upward thrust thereof, the extreme forward portion of said area lying in a plane extending through the open end of said jaw below said top wall.
4. In a railway car truck, a frame member having a brake hanger bracket with an angularly disposed jaw defined by top and bottom walls merging in a throat, a loop type brake hanger having its upper member seated in said throat, the top surface of said throat having an area for abutment of said member on upward thrust thereof, the extreme forward portion of said area lying in a plane forming an acute angle with the plane of said hanger when said brakes are applied, a wear plate seated on said lower wall and having a channel portion underlying said member, and means securing said plate in position on said lower wall, said means being secured against rotation by engagement with said upper wall.
5. In a railway truck, a frame member having a bracket with an angularly disposed brake hanger jaw defined by top and bottom walls merging in a throat, a wear plate seated on said bottom wall, aligned openings in said walls and in said wear plate, means in said aligned openings securing said wear plate on said bottom wall, said means being secured against rotation by cooperation with the aperture in said top wall, and a loop brake hanger having a top member seated on said plate in said throat, the upper surface of said throat having an arcuate form for abutment of said member, and the forward portion of said surface lying in a plane extending through the open end of said jaw below said top wall.
6. In a railway car truck, a frame member having a bracket with a brake hanger jaw defined by top and bottom walls merging in a throat, a wear plate secured on said bottom wall and having a channel at the inner end thereof, and a brake hanger having its top member seated in said channel within the said throat, the top surface of said throat having an arcuate form and the forward portion of said surface lying in a plane extending through the open end of said jaw below said top wall, said bottom wall lying in a plane diverging from the horizontal through an arc at least equal to the maximum arc which said hanger swings from the perpendicular under operative conditions.
7. In a railway car, a frame member, an integral brake hanger bracket having an angularly disposed jaw with open sides and an open end, said jaw having top and bottom walls merging in a throat portion, a wear plate secured to said bottom jaw, and a hanger seated on said plate in said throat portion, the upper surface of said throat portion having an area for abutment of the top member of said hanger and the lower wall of said jaw being disposed at an angle varying from the horizontal an amount equal to or greater than the maximum angle at which said hanger may vary from the perpendicular under operative conditions, the extreme forward portion of said area lying in a plane forming an acute angle with a vertical plane.
8. In a railway car truck, a frame member having a bracket with a brake hanger jaw defined by top and bottom walls merging in a throat, and a loop hanger seated in said throat, the top surface of said throat having an area for abutment of the top member of said hanger, the forward portion of said area lying in a plane forming an acute angle with the plane of said hanger when said brakes are applied, and a wear plate secured on said bottom wall and affording an arcuate seat at its inner end for said hanger and closure means for said jaw at its outer end.
9. In a railway car truck, a frame member having a bracket with a brake hanger jaw defined by top and bottom walls merging in a throat, a loop hanger seated in said throat, the top surface of said throat having an arcuate form for abutment of the top member of said hanger, the forward portion of said surface lying in a plane forming an acute angle with the vertical and extending through the open end of said jaw, and a wear plate secured on said bottom wall and having a channel portion underlying said member.
10. In a railway car truck, a frame member having a bracket with a brake hanger jaw defined by top and bottom walls merging in a throat, a wear plate secured on said bottom wall and having a channel at the inner end thereof, and a loop-type brake hanger having its top chord seated in said channel within the said throat, the top surface of said throat having an arcuate form and the forward portion of said surface lying in a plane intersecting the horizontal plane defined by the axis of said chord outwardly of said throat.
11. A brake hanger bracket having a jaw defined by top and bottom walls merging in a throat, a hanger seated in said throat, said bottom wall diverging from the horizontal through an arc at least equal to the maximum arc which said hanger may swing from the perpendicular under operative conditions, the upper surface of said throat having an arcuate formation for abutment of said member, the forward portion

of said formation lying in a plane intersecting the horizontal plane defined by the top outer edge of said lower wall outwardly of the mouth of said jaw, and a wear plate secured on said bottom wall and having at its rear end an arcuate seat for said hanger and at its forward end closure means for said jaw.

12. A brake hanger bracket having an angularly disposed jaw defined by top and bottom walls merging in a throat, a wear plate secured on said bottom wall, and a loop type hanger seated on said plate in said throat, said bottom wall being disposed at an angle diverging from the horizontal an amount at least equal to the maximum angle said hanger may diverge from the perpendicular under operating conditions, the upper surface of said throat having an arcuate configuration for abutment of the top member of said hanger on upward thrust thereof, 20 the forward-most portion of said configuration lying in a plane forming an acute angle with the vertical.

13. In a railway car truck, a frame member having a brake hanger bracket with an angularly disposed jaw defined by top and bottom walls merging in a throat, and a loop type brake hanger having its upper member seated in said throat, the top surface of said throat having an area for abutment of said member on upward thrust thereof, the extreme forward portion of said surface lying in a plane which forms an acute angle with the plane of said hanger when said brakes are applied, and a wear plate secured on said bottom wall and affording at its rear end an arcuate seat for the top chord of said hanger and at its forward end closure means for said jaw.

14. A brake hanger bracket having a jaw defined by top and bottom walls merging in a throat, and a hanger seated in said throat, the upper surface of said throat having an area for abutment of said hanger, the extreme forward portion of said area lying in a plane forming an acute angle with the plane of said hanger when the brakes are in applied position, and a wear plate secured to said bottom wall and having at its rear end a seat for said hanger and at its forward end closure means for said jaw.

15. A brake hanger bracket having a jaw defined by top and bottom walls merging in a throat, and a loop hanger seated in said throat, the upper portion of said throat having an area for abutment of said hanger when the brakes are applied to urge said hanger upwardly, the forward portion of said area lying in a plane forming an acute angle with the plane of said hanger when said brakes are in applied position, and a wear plate positioned in said jaw and affording at its rear end a seat for said hanger and at its forward end a closure means for said jaw.

16. A brake hanger bracket having a jaw defined by top and bottom walls merging in a throat, and a loop hanger having a top chord thereof seated in said throat, said throat having in its top portion an area for abutment of said hanger when the brakes are applied to give an upward thrust thereto, the forward portion of said area lying in a plane forming an acute angle with the vertical, and a wear plate positioned in said jaw and affording at its rear end a seat for said hanger and at its forward end a closure means for said jaw.

DAVID M. LIGHT.
